DESIGN FOR A DOUBLE SPECTACLE CASE

Nelson Kalnitz and Charles E. Appling,
Los Angeles, Calif.

Application April 10, 1946, Serial No. 128,446

Term of patent 14 years

(Cl. D57—1)

To all whom it may concern:

Be it known that we, Nelson Kalnitz and Charles E. Appling, citizens of the United States, residing at Los Angeles, in the county of Los Angeles and State of California, have jointly invented a new, original, and ornamental Design for Double Spectacle Case, of which the following is a specification, reference being had to the accompanying drawing, forming part thereof.

Figure 1 is a plan view of a double spectacle case when in open position showing our new de-

sign; Fig. 2 is an end edge view of the structure shown in Fig. 1; Fig. 3 is a plan view of the double spectacle case shown in Fig. 1, when said case is in closed position, and Fig. 4 is an end edge view of the structure shown in Fig. 3.

We claim:

The ornamental design for a double spectacle case, as shown.

NELSON KALNITZ.
CHARLES E. APPLING.
